UNITED STATES PATENT OFFICE

154,750

DESIGN FOR A PRESSURE COOKER

John Cotter, Chicago, Ill., assignor to Speed-Meal Corporation, Racine, Wis., a corporation of Delaware

Application June 21, 1946, Serial No. 130,906

Term of patent 14 years

(Cl. D44—1)

To all whom it may concern:

Be it known that I, John Cotter, a citizen of the United States, residing at Chicago, in the county of Cook and State of Illinois, have invented a new, original, and ornamental Design for Pressure Cooker, of which the following is a specification, reference being had to the accompanying drawing, forming a part thereof.

Figure 1 is a plan view of the cooker showing my new design.

Figure 2 is a side elevational view.

Fig. 3 is a front view.

The knob at the center of the cover and the discs in the outer ends of the handles are shaded to indicate the color of red.

I claim:

The ornamental design for a pressure cooker, as shown and described.

JOHN COTTER.
